UNITED STATES PATENT OFFICE.

ALPHONSO S. HARRIS, OF CHELSEA, MASSACHUSETTS.

GAS-BURNER.

SPECIFICATION forming part of Letters Patent No. 269,931, dated January 2, 1883.

Application filed November 27, 1882. (No model.)

To all whom it may concern:

Be it known that I, ALPHONSO S. HARRIS, of Chelsea, State of Massachusetts, have invented an Improvement in Gas-Burners, of 5 which the following is a specification.

This invention relates to gas-burners; and it consists in the construction and combination of the divers devices embodied therein, as hereinafter more particularly and fully set forth 10 and claimed.

Figure 1 is a perspective view of a gas-burner embodying my invention. Fig. 2 is a longitudinal vertical section of Fig. 1, taken through the check-lever and one of the radial 15 arms, and also showing in elevation a section of a supply-pipe and its stop-cock connected with the burner. Fig. 3 is a horizontal section taken, as on line W, Fig. 2, through the pillar, the check stem and lever, and the 20 radial arms, the tips and their supporting-sockets being shown in central vertical section. Fig. 4 shows in elevation the check stem and sleeve as detached from the burner and from each other. Fig. 5 shows the same 25 parts as in Fig. 4, but as connected for use and in longitudinal section.

In said views, *a* represents the pillar of the burner, shown as mounted upon a supply-pipe, *b*, in which is arranged the usual stop-cock *c*, 30 by which the supply of gas is let on or shut off from the burner. In pillar *a* are secured the radial conduit-arms *d*, upon the outer ends of which are mounted the sockets *e*, which receive and support the tips *f*, as shown.

For the purpose of checking and regulating the flow of gas to the tips after it has passed cock *c*, I employ a sleeve, *h*, which is formed with an enlarged externally-threaded section, *i*, and a diminished smooth section, *j*. This 35 sleeve is secured in pillar *a* by engaging corresponding interior screw-threads formed therein, and it may be locked firmly in position in the pillar by seating its shoulder, formed at the intersection of the enlarged portion *i* and diminished portion *j*, against a corresponding shoulder in the pillar, as shown in Fig. 2; or it may fit so closely in the pillar as not to be disturbed when the check-stem is actuated. The axial passage in said sleeve is screw-threaded nearly throughout its length, as

shown in Figs. 2 and 5, and a stem, *m*, is threaded upon its exterior to fit closely but move freely in the sleeve. In the lower portion of said stem is formed an axial passage, as shown in Figs. 2 and 5, with which the 55 transverse passages *n* directly communicate, said transverse passages being at the same distance apart as are similar passages, *l*, formed in sleeve *h*. In said sleeve is inserted a check pin or screw, *t*, for convenience of both forming holes *l* in the sleeve and *n* in stem *m*, and also for adjusting the check in the former, said sleeve being first screw-threaded in its interior, and then said pin *t* being inserted, after which stem *m* is inserted in the sleeve and 60 firmly seated upon pin *t*, when the transverse holes *l* *n* are drilled through the wall of both the sleeve and stem, and thus exactly correspond. When thus prepared the sleeve is inserted in the pillar by means of a screw-driver, 65 the base of the sleeve being slotted, as shown at *k*, for that purpose, when stem *m* may be inserted through the axial coincidentally-threaded passage in the head of the pillar, and is turned into the sleeve till arrested by 70 pin *t*, when the actuating-lever *v* is secured in the head of the stem, as shown, the several parts being so arranged in relation to each other that when lever *v* is moved in one direction against an arm, *d*, the gas will be in 75 full flow to tips *f*, and when said lever is moved in the opposite direction against one of said arms the flow of gas to the tips will be reduced to the lowest desired quantity, thereby rendering it practical to regulate the flow 80 of gas at any desired point between a full head and such minimum quantity.

Instead of threading stem *m* in the head of pillar *a*, it may be packed therein, if desired.

The flow of the gas through pipe *b*, sleeve *h*, 85 stem *m*, holes *n* *l*, into the chamber in pillar *a*, around the upper portion of the sleeve and stem, and thence through arms *d* to the tips, will be apparent from an inspection of the drawings.

By arranging the arms *d* radially in the pillar, as shown, the transverse openings *l* *n* may be sufficiently small to afford the requisite check to the flow of gas, and yet not be entirely closed by the rotation of the stem when lever 90

v is moved from the position of maximum flow of gas to the opposite position against another arm *d*, as before explained.

I claim as my invention—

- 5 1. The combination of hollow pillar *a*, sleeve *h*, and stem *m*, having the respective axial and transverse passage, and lever *v* for actuating said stem, substantially as specified.
- 10 2. In combination with sleeve *h* and stem *m*, having the respective axial and transverse passages, and means for actuating said stem, the stop pin *t*, arranged in said sleeve to arrest the movement of the stem therein when the respective transverse passages *l n* are coincident, substantially as specified.
- 15

3. In combination with pillar *a*, sleeve *h*, stem *m*, and lever *v*, all arranged to operate as described, a plurality of radial conduit arms *d*, arranged around said pillar to gage and control the movement of said lever and 20 the requisite relative adjustment of the transverse passages in said stem and sleeve, substantially as specified.

ALPHONSO S. HARRIS.
